(57) **CLAIM**

The ornamental design for an electronic display controller with graphical user interface, as shown and described.

DESCRIPTION

The FIGURE is a front view of an electronic display controller with graphical user interface showing my design. The outermost rectangle, shown partially in broken lines, depicts the electronic display controller. The broken line portion of the electronic display controller forms no part of the claimed design. All other broken lines depict portions of the graphical user interface and form no part of the claimed design.

1 Claim, 1 Drawing Sheet
